United States Patent Office

Des. 190,936
Patented July 18, 1961

190,936

MICROFILMER

Theodore G. Clement, Rochester, N.Y., assignor to Eastman Kodak Company, Rochester, N.Y., a corporation of New Jersey

Filed Feb. 16, 1961, Ser. No. 63,952

Term of patent 14 years

(Cl. D61—1)

Fig. 1

Fig. 2

Fig. 3

FIG. 1 is a front perspective view of a microfilmer showing my new design;

FIG. 2 is a front perspective view from the opposite side thereof; and

FIG. 3 is a rear perspective view thereof.

I claim:

The ornamental design for a microfilmer, as shown.
